AUTOMATIC SAFETY PLUNGER

Samuel L. Belknap, Los Angeles, Calif.

Application October 13, 1939, Serial No. 299,303

2 Claims. (Cl. 70—1.5)

This invention relates to automatic safety plungers, and has for an object the provision of a suitable device wherein safe doors, or other instrumentalities, may be securely held closed 5 to the door housing to prevent removal of said door incident to an external tampering with the door.

Particularly, this invention contemplates an improvement upon my Automatic safety plunger 10 described and set forth in United States Letters Patent No. 1,919,647, granted July 25, 1933. Reference is also made to Letters Patent granted to me, No. 1,887,866, issued November 15, 1932, for Double door floor safes.

The present invention has applicability to safes of the type mentioned in the Letters Patent aforementioned and wherein the safe body is adapted to be surrounded by and encased in concrete or other substance within a floor. Safes of this character 20 are of great utility in stores, offices, and the like, when it is desired to deposit money therein which must be left within the safe during the day or over night. Such a safe, due to its compactness and the fact that by being secured within the 25 floor, does not take up useful space in an office, and has caused its general adoption in the business industry. It has been found under actual service conditions that the type of safe herein depicted in part, when secured within the floor, is 30 not easy of removal and assures the utmost protection against either professional safe blowers or an amateur safe blower.

Whereas in my Letters Patent No. 1,919,647, I have provided an automatic safety plunger adapted to accomplish in part the locking object of the present invention, still it is possible, under certain conditions, to so destroy the main lock on the safe door and perhaps by suitable implement engage the automatic safety plunger to retract 40 the same so that the safe door may be rotated or otherwise moved so as to remove the same from the safe body. The present invention is adapted to overcome the deficiency just mentioned, in that the device to be described is arranged so 45 that the plunger is not permitted to have retrograde movement after it has once been moved into locking engagement with the safe body, and hence the door is incapable of being removed from said body, irrespective of rotation thereof or destruction 50 of its main locking mechanism.

Other objects of the invention include an automatic safety plunger and its operating mechanism which is simple of construction, inexpensive in cost of manufacture, and capable of producing 55 efficient results.

With the above mentioned and other objects in view, the invention consists in the novel and useful provision, formation, construction, association, and relative arrangement of parts, members and features, all as shown in a certain embodiment in the accompanying drawing, described generally, and more particularly pointed out in the claims.

5 In the drawing:

Figure 1 is a fragmentary top plan view of a 10 safe provided with a door, said door incorporating the automatic safety plunger.

Figure 2 is a sectional view on the line 2—2 of 15 Figure 1.

Figure 3 is a sectional view on an enlarged 20 scale, taken on the line 3—3 of Figure 1, and,

Figure 4 is a fragmentary sectional view, the plunger being moved from a non-flange engaging position of the safe body to a flange engaging position of the same body.

Referring now with particularity to the drawing, in the figures, I have illustrated a safe body 1 of a type which is particularly adapted to be sealed or encased within some medium, such as concrete 2. It is to be observed that the body has 25 a tapered outer surface 3, a base 4 having an external flange 5, whereby when the material 2 encompasses the body, the flange is interlocked with said material 2 so as to prevent removal of the safe body therefrom. This safe body adjacent its top 6 is provided with two spaced apart internal flanges 7 and 8. These flanges are both provided with seats 9 and 10, respectively, and external and internal safe doors 11 and 12 are adapted to be received upon the seats 9 and 10. 30 The safe doors are identical in construction, and one will be described.

Taking the door 11 by way of example, the said door is substantially circular and provided with two portions of different diameter 13 and 14. 40 The portion 13 is adapted to be received within the confines of the safe body, while the portion 14 is a flange. This flange rests upon the seat 9 when the door is closed, see Figure 3. Furthermore, the end 15 of the body 1 is adapted to be substantially flush with the top surface of the door when the door is closed. The portion 13 of the door is recessed inwardly from the bottom wall, as shown at 16, to receive a key-operated lock (not shown). However, in Figure 1, the key 45 opening 16a is illustrated. When a proper key is inserted within the opening 16a, the tumblers of the lock may be operated so as to retract a bolt 17 from beneath the flange 7. This bolt 17, 50 acting in conjunction with a segmental lug 18 55

5 diametrically disposed relative to said bolt 17, acts to securely hold the door locked beneath the flange of the safe body and to prevent its removal from said body. Thus, while the door is in its seated position on the body, the door is capable of being completely rotated, although it is possible to provide the door for limited rotation, as is self-evident. For the purpose of holding the lock case in position within the recess of the door, 10 I have provided a plate 19. This plate may be secured to the bottom surface of the door in any approved manner, such as through the medium of screws, rivets, or the like, although it is intended that the plate should not be so rigidly held that a direct punching downwardly upon the lock would not permit the plate to flex. A flexing of the plate permits one or more lock bolts or plungers of the present invention to move beneath flange 7 to effectively prevent removal of 15 the door from the safe body. These bolts or plungers may be termed the secondary locking means and are designated as an entirety by the numeral 20. In Figure 1, I have provided two of said devices, as illustrated in dotted lines.

20 Referring to Figures 3 and 4, part 13 of the body is formed with a radially extended bore 21, within which is received the plunger 22. This plunger includes a bolt formed at the inner end thereof, with a bore 23 within which is positioned a coil spring 24, which coil spring bears against the end wall 25 bounding the bore 21, whereby the 25 said plunger is normally urged outward from the bore 21 to position the plunger beneath the flange 7, resultant upon a flexing of the plate 19 sufficient to release a locking stud 26 from engagement with said plunger. As shown in Figure 3, this stud is secured to the plate 19 and normally is received in a transverse opening 27, which 30 communicates with the bore 21. This plunger is provided with a transverse bore 28 which is in axial alignment with the bore 27 when the plunger is fully retracted within the bore 21, at which time the stud 26 not only passes completely through the bore 27 but is received within said bore 28 to hold the bolt or plunger 22 in its retracted position, the spring 24 being compressed, 35 see Figure 3. The body 13 is provided with bores 29 and 30 lying in the same axis and the bore 30 is adapted to receive a pin or stud 31 which may be gravity or spring-actuated in one direction. When the bolt or plunger 22 is in the position shown in Figure 3, the pin or stud 31 is confined within the bore 30, with the bottom of said pin resting on a portion of the periphery of the 40 plunger. However, when the stud 26 is released from engagement with the said bolt or plunger, as illustrated in Figure 4, and the bolt or plunger 22 actuated outwardly from the body by the spring 24, the pin or stud 31 will drop behind the bolt or plunger and rest upon the spring 24. The bolt or plunger 22 is thus prevented from retrograde movement. Hence, even though the main lock case is punched inwardly, the secondary locking means will be actuated into position so that the 45 door cannot be removed from the safe body.

50 As two doors are provided, it becomes evident that anyone trying to make unlawful access within the safe is faced with a long, arduous job in attempting to remove the doors, even though it was possible to chip away all the concrete and 55 remove the safe bodily. As a rule, thieves are not prone to stay in a neighborhood long enough to complete a removal of the safe, nor attempt to work upon the safe doors to remove the same.

60 75 Assemblage of the secondary locking mechanism

5 for the door is comparatively simple, in that the safe door may be turned upside down, the pin or stud 31 dropped through the bores 29 and 30 so that said pin is completely received within the bore 30, whereupon the plunger, with its spring, may be inserted within its bore and the plate 19 positioned so that the stud 26 may enter the openings 27 and 28 to hold the secondary locking mechanism inactive or in the position shown in Figure 3.

10 Obviously, when the secondary locking means has been actuated, it then becomes necessary to remove the safe bodily from the concrete or other encasing material. The doors will have to be drilled in order to release the pins or studs 31 and likewise the safe body itself must be drilled in order to retract the plungers from beneath the flange.

15 The general inaccessibility of a safe of this character renders it most difficult to work upon 20 and therein lies a feature of safety for the contents within the safe. A charge of explosive poured into the lock will do nothing more than warp the plate 19 and allow the secondary locks to operate, nor would the use of acid be of any 25 consequence, because the lug 18 and the bolt 17 would still be in position beneath the flanges, and if any blow was struck, the plate 19 would be immediately twisted so that the secondary lock 30 means would come into position beneath the flange.

35 The double door feature is important and, as stated before, both doors are provided with secondary locking means for which reason the inner door is not detailed as to description.

35 I claim:

40 1. A safe comprising a vertically disposed body having an entrance at the top thereof, a door for the body, there being an inwardly extending horizontally disposed flange on which the door rests, a lock for the door having a bolt adapted to be moved beneath the flange when in locking position, said lock extending through the door, a plate on the under side of the door, a spring actuated bolt urged horizontally into flange engaging position mounted on the door, means associated 45 with the plate for normally holding the spring actuated bolt retracted but adapted to release it when the plate is moved such as on punching the lock, said door having a recess directly above said spring actuated bolt, and a locking element disposed in said recess and bearing against the spring actuated bolt in such manner that said locking element will automatically move into the axial plane of the bolt to prevent retrograde movement of the latter when the bolt is moved into flange engaging position.

50 2. A safe comprising a vertically disposed body having a circular entrance at the top thereof, there being an inwardly extending horizontally disposed circular flange at the entrance on which the door rests, a lock for the door having a bolt adapted to be moved beneath said flange when in locking position enabling the door to be rotated while in locked position, said door having horizontally disposed elongated recesses opening through the edge thereof, spring actuated bolts mounted in the recesses and adapted to be projected by the springs into positions beneath said 55 flange, means connecting the spring actuated bolts to the lock for normally holding the spring actuated bolts in retracted positions but adapted to release them when the lock is disturbed from its normal position such as on punching the lock, 60 65 70 75 75

said door having vertically disposed elongated recesses directly above the spring actuated bolts and opening through the walls of the horizontally disposed recesses, and freely slideable pins in said vertically disposed recesses normally seated on said spring actuated bolts in such relation to the

inner ends thereof that the pins drop by gravity into positions inwardly of the bolts to prevent retrograde movement of the latter when the bolts are moved into positions beneath the flanges.
